FIG. 1. FIG. 2.

FIG. 3.

FIG. 4.

Inventor

R. W. Boje, Jr.

By *A. Buntelby Jr.* attorney.

UNITED STATES PATENT OFFICE.

BUDOLF W. BOJE, JR., OF BUFFALO, NEW YORK.

TONGUE-BALL.

1,352,047.

Specification of Letters Patent.

Patented Sept. 7, 1920

Application filed January 23, 1919. Serial No. 273,553.

To all whom it may concern:

Be it known that I, RUDOLF W. BOJE, Jr., a citizen of Germany, residing at Buffalo, in the county of Erie and State of New York, have invented certain new and useful Improvements in Tongue-Balls; and I do hereby declare the following to be a full, clear, and exact description of the invention, such as will enable others skilled in the art 10 to which it appertains to make and use the same.

This invention relates to toys, and the primary object of the invention is to provide an improved hollow rubber ball having a head printed, stamped or molded thereon and a thin hollow rubber member, which is adapted to be projected out of the ball through the mouth of the head formed thereon, when the ball is depressed so as to 20 simulate the appearance of the head sticking out its tongue.

A further object of the invention is to provide an improved rubber ball having a man's head stamped thereon and a thin 25 flexible hollow member associated with the ball and adapted to represent the tongue of the man's head, which is adapted to be forced inward and outward of the ball by depressing and releasing the ball.

A still further object of the invention is to provide an improved toy of the above character, which is durable and efficient in use, one that is simple and easy to manufacture, and one that can be placed upon the 35 market at a reasonable cost.

With these and other objects in view the invention consists in the novel construction, arrangement and formation of parts, as will be hereinafter more specifically 40 described, claimed and illustrated in the accompanying drawings, forming a part thereof, in which:

Figure 1 is a front elevation of the improved toy.

Fig. 2 is a side elevation of the toy.

Fig. 3 is a view similar to Fig. 2, showing the tongue of the toy in its projected position, and

Fig. 4 is a vertical section taken on the line 4—4 of Fig. 1 and showing the tongue, when it is in its collapsed position.

Referring to the drawings in detail, wherein similar reference characters designate corresponding parts, throughout the 55 several views, the numeral 1 generally indicates the improved toy, which includes a

hollow circular body 2 formed of rubber or other similar flexible material. The body 2 has molded thereon the figure of a head 3 and, as shown in the drawings, this figure 60 represents a man's head, but it is to be understood that any suitable character may be molded with the body. The mouth 4 of the head 3 has an oval shaped opening 5 formed therein, through which is adapted to be projected a hollow tapered member 6, which 65 constitutes the tongue of the man's head. The member 6 is gradually tapered toward the free and thereof and suitably painted so as to simulate the human tongue. The member 6 has the walls thereof formed relatively thinner than the walls of the body 2, so that when the body is depressed, the air confined in the body seeking an outlet, will force the member 6 outwardly. The edges of the 70 member 6 are turned outwardly as at 7 and vulcanized or otherwise suitably secured to the inner walls of the opening 5. The member 6, if so desired, may be formed integral with the body 2.

In operation of the improved device, the sides of the body 2 are squeezed or depressed by the fingers and the member 6, being formed of relatively thinner rubber than the walls of the body, will be forced or projected outwardly of the body by the air confined therein and thus simulate the appearance of a man sticking out his tongue. Upon releasing the body, the member 6 will be drawn inwardly into the body by the suction 85 of the air resuming its normal position.

From the foregoing description, it can be seen that an improved toy is provided, which is simple to operate and will be highly amusing to children and the like.

In practice, I have found that the form of my invention illustrated in the accompanying drawings and referred to in the above description, as the preferred embodiment, is the most efficient and practical; yet 100 realizing the conditions concurrent with the adoption of my device will necessarily vary, I desire to emphasize that various minor changes in details of construction, proportion and arrangement of parts may be resorted to, when required without sacrificing any of the advantages of my invention as set forth.

What I claim as new is:

A toy comprising an elastic hollow body 110 of substantially spherical shape representing the head of a human being and having

an elliptical shaped opening to provide a mouth, a projection formed on said body and disposed above the opening and shaped to form a nose, said body having eyes applied thereon and disposed on each side of the nose, and a tapered elastic member having one end closed and its open end secured to the interior of the body about the opening, so that said member may be projected

and retracted in the body by squeezing and 10 releasing the pressure on said body.

In testimony whereof I affix my signature in presence of two witnesses.

RUDOLF W. BOJE, JR.
